Primary Examiner—Robert M. Spear

(74) Attorney, Agent, or Firm—Gerard J. McGowan, Jr.

(57) **CLAIM**

The ornamental design for a spigot and collar assembly, substantially as shown and described.

DESCRIPTION

FIG. 1 is a top, rear and left side perspective view of a spigot and collar assembly with a container shown in dotted lines for environmental purposes only and forming no part of the claim;

FIG. 2 is a top plan view of the spigot and collar assembly; FIG. 3 is a bottom plan view thereof;

FIG. 4 is a front view thereof;

FIG. 5 is a right side view thereof (the left side being a mirror image);

FIG. 6 is a rear view thereof; and,

FIG. 7 is an exploded perspective view of the spigot and collar assembly, with a portion of a container in dotted lines for environmental purposes only and forming no part of the claim. A portion of the collar assembly is shown broken away for clarity of disclosure.

1 Claim, 4 Drawing Sheets
